UNITED STATES PATENT OFFICE.

STANLEY LEECH, OF DETROIT, MICHIGAN.

WRINGER.

Application filed April 1, 1922. Serial No. 548,674.

To all whom it may concern:

Be it known that I, STANLEY LEECH, a subject of the King of Great Britain, residing at Detroit, in the county of Wayne and State of Michigan, have invented certain new and useful Improvements in Wringers, of which the following is a specification, reference being had therein to the accompanying drawings.

10 In my pending application filed Dec. 2, 1921, Serial No. 579,310 there is disclosed a clothes wringer which includes a quick release device for the tensioned or spring pressed wringer roll, and it is in connection with this type of wringer that we have further improvements.

First, I have simplified the construction of the quick release device, not only from a manufacturing standpoint, but such change 20 has made it more sensitive so that a minimum movement of the device will cause instant release of the pressure roll of the clothes wringer.

Second, associated with the quick release 25 device is means for increasing and decreasing the tension of a spring associated with the pressure roll of the wringer, said means being movable with a portion of the quick release device when the same is actuated to release spring pressure, otherwise the quick release device retains said means in an operative position for increasing or decreasing spring pressure on the wringer roll.

Third, my invention includes novel water 30 deflectors and sheds which are disposed at the ends of the wringer rolls to prevent any great quantity of water from reaching bearings, springs, gear wheels and the like at the ends of the wringer rolls and it is in consequence of these water deflectors or 35 sheds that the enumerated parts possess greater longevity. Also, the wringer can be more easily retained in a sanitary condition and clothes are prevented from being wound 40 about and injured by spindles or movable end parts of the wringer.

Fourth, my invention further includes a shiftable drain board or member permitting 45 of clothes and water being delivered at a desired side of the wringer, and novel means is employed for locking a drain board or member in said position.

Fifth, my invention includes a somewhat 50 better construction than disclosed in our pending application and such construction

will be hereinafter specifically described and then claimed.

Reference will now be had to the drawings, wherein—

Figure 1 is a front elevation of the clothes 60 wringer partly broken away and partly in longitudinal section;

Fig. 2 is a vertical cross sectional view taken on the line II—II of Fig. 1;

Fig. 3 is a horizontal sectional view taken 65 on the line III—III of Fig. 1;

Fig. 4 is an enlarged horizontal sectional view taken on the line IV—IV of Fig. 1;

Fig. 5 is an enlarged vertical cross sectional view of the quick release device of the 70 wringer;

Fig. 6 is an enlarged cross sectional view of a spring connection forming part of the wringer, and

Fig. 7 is a horizontal sectional view of the 75 same.

In the drawings, the reference numeral 1 denotes a one piece wringer frame that is substantially inverted U shape in elevation, said frame having opposed arms 2 and 3 and 80 said frame is substantially channel shaped in cross section with the open sides thereof confronting and with the front and rear walls of the frame provided with a multiplicity of openings 4 which reduce weight 85 and facilitate casting or otherwise making the frame.

In the arms 2 and 3 are lower journals or 90 bearings 5 and 6 retained in said arms by the loop ends 7 of a transversely disposed member 8 which has its looped ends detachably held in the lower ends of the arms 2 and 3 by screws 9 or other fastening means. The journals 5 are slotted or bifurcated to receive the spindles 10 and 11 of a lower 95 wringer roll 12 and the spindle 10 has a gear wheel 13, while the spindle 11 is adapted to receive a crank to be driven by hand or be coupled to a motor or other power devices.

Above the journals 5 are inverted journals 100 14 for the spindles 15 of an upper wringer pressure roll 16 and one of said spindles has a gear wheel 17 meshing with the gear wheel 13, said gear wheels being designed so that the gear wheels 17 may be readily moved 105 into and out of mesh with the gear wheel 13. These gear wheels may be housed within a casing 18 forming part of the arm 2 and provided with a detachable cover 19.

The confronting ends of the journals 5, 6 110

and 14 are recessed, as at 20 to receive coiled expansion springs 21 and the expansive force of these springs is adapted to quickly elevate the journals 14 so that the same may release the pressure roll 16 relative to the roll 12 or clothes being moved between said rolls.

Engaging the journals or bearings 14 are the curved ends of a bowed spring 22, said 10 spring having a central raised portion 23 and this spring is adapted to be placed under tension and serve both ends of the pressure roll 16 so as to bodily hold said roll relative to the roll 12, the single spring being in contact 15 to separate springs that are at times used in the arms 2 and 3 of the wringer frame.

Reference will now be had to that feature of my invention which includes the quick release device for placing the spring 22 under tension and quickly releasing such tension when occasion so requires.

Mounted on or in the arched wall 24 of the frame 1 for instance by screw threads 25, 25, is the lower end of a tubular post 26 having its upper end provided with outwardly projecting diametrically disposed studs or pins 27. The post 26 is cylindrical and slidably mounted thereon is a quick release sleeve 28 having opposed segment shaped enlargements 29 affording interior recesses 30 and in these recesses are tapered supports 31 for the pins 27. The tapered supports 31 taper inwardly from the lower 35 ends of said supports to the upper ends thereof and it is on the upper ends of said supports that the pins 27 rest. The supports 31 cooperate with side walls of the recesses 30 in providing grooves affording 40 clearance for the outer ends of the pins 27, at the side of the supports, when shifted from beneath the pins, and this is accomplished by partially rotating the sleeve 28 on the post 26 in either direction, such 45 movement being facilitated by opposed handles or projections 32 carried by the sleeve 28.

Adjustable in the upper end of the sleeve 28 is a screw 33 that is in threaded engagement with the closed upper end of said sleeve, said screw having its outer end provided with a knurled head 34 and its inner end with a stem 35 that slidably fits in the post 26 and prevents lateral displacement of the lower end of the screw. The lower end of the stem 35 is reduced and provided with an annular groove 37 to receive a split ring or retaining member 36 which is employed for holding a stirrup 38 on the lower end of the stem 35, and said stirrup loosely engages the central raised portion 23 of the spring 22. The stem 35 is rotatable relative to the stirrup and the lower end of said stem bears on the central portion of the spring 22 to flex said

spring and place it under tension when the screw 33 is rotated. The expansive force of the spring through the connection of the sleeve 28 with the screw 33 holds the supports 31 under the ends of the pins 27 to such an extent that the sleeve 28 will not rotate while the screw 33 is being adjusted, therefore the tension of the spring 22 can be adjusted at any time the quick release device is in a set position, and I attach considerable importance to this feature of my invention. Assuming that the spring 22 is stressed and it is desired to release the pressure on the roll 16, it is only necessary to strike one of the handles 32 and the sleeve 28 will be partially turned, in one direction or the other, thereby moving the supports 31 from under the pins 27, permitting the sleeve 28 to be raised, and thus release the tension of the spring 22. When the sleeve 28 is shifted upwardly the grooves at the sides of the supports 31 afford clearance for the pins 27 and with said supports longitudinally of the sleeve, it is far easier to locate said pins on the supports than if the support were very short or pin-like. The opposed handles 32 permit of the quick release device being easily reset and it is apparent from the novel construction of the same that the device is very sensitive and consequently an exceedingly quick release of the pressure roll 16 may be accomplished.

Considering another feature of the invention, reference will be had to Figs. 1 and 2 showing water deflectors at the ends of the rolls 12 and 16. The water deflectors are in the form of slotted and apertured partitions 39, said partitions, being slotted, as at 40 to provide clearance for the spindles 15, and apertured, as at 41, to provide clearance for the spindles 10 and 11. The partitions are set in the open sides of the arms 2 and 3 and said partitions are transversely corrugated or roughened so as to prevent wet clothes from adhering thereto. At the lower ends of the partitions are water shedding flanges 42 projecting inwardly under the roll 12, and at the sides of said roll are pivoted guards 43 adapted to prevent clothes from being carried under said roll. The partitions 39 are held in place by the spindles 10, 11 and 15 and by inwardly projecting lugs 44 carried by the arms 2 and 3, said lugs being best shown in Fig. 2.

A further feature of the invention is a reversible drain apron or pan 45 having its side edges reinforced and stiffened by supporting bars 46 which are adapted to engage under the flanges 42 of the partitions 39 and on the loop ends 7 of the transverse member 8. One of the bars 46 has recesses 47 adjacent its ends to receive a spring pressed detent or catch 48 carried by the journal or bearing 5, and said detent extends through the partition 39 at the bearing 5.

and through the detachable cover of the casing 18. By pulling on the outer end of the detent 48 it may be detracted and the drain apron or pan may be shifted from the position shown in Fig. 2 to a reverse position, and in either position water wrung from clothes will drain back into the tub or receptacle above which the wringer is mounted.

While in the drawings there is illustrated a wringer which has been put into practice and so far found satisfactory, yet it is to be understood that the various features of my invention are susceptible to such changes as are permissible by the appended claim.

What I claim is:—

A quick tension release device for a clothes wringer of the roll type having a stationary frame and a tension screw for regulating the tension of a roll, said device comprising a tubular post mounted on said frame with

said screw extending through said post, pins mounted in the outer wall of said post at the upper end thereof, a shiftable sleeve in 25 screw-threaded engagement with said screw and surrounding said post, enlargements on said sleeve affording recesses in the inner wall of said sleeve and into which recesses said pins extend, and supports in the sleeve 30 recesses and extending longitudinally thereof to co-operate with the wall of said sleeve in forming guide grooves for said pins, said pins resting normally on said supports and adapted to be shifted off of said supports by 35 said sleeve to permit a quick movement of said sleeve.

In testimony whereof I affix my signature in presence of two witnesses.

STANLEY LEECH.
